INTERNAL COMBUSTION ENGINE

Philip A. Tanner, Waukegan, Ill., assignor to
 Johnson Motor Company, Waukegan, Ill., a
 corporation of Delaware

Application December 31, 1934, Serial No. 759,862

10 Claims. (Cl. 123—73)

This invention relates in general to an improvement in internal combustion engines and more particularly to two-cycle engines in which oil is mixed with the gasoline for lubrication of the 5 engine parts.

An important object of the invention is in the provision of means for improving the lubrication of an engine of this type.

A further object of the invention is to prevent 10 excess oil being carried into the combustion chamber and from fouling and interfering with the spark plugs.

Another object of the invention is in the provision of means for preventing excess oil from 15 accumulating in the crank case and for discharging it therefrom.

A still further object of the invention is in the provision of means for varying the lubricating conditions dependent upon throttle or spark (or 20 both) adjustments.

In the drawings, Fig. 1 is a sectional view of a two-cycle engine embodying the invention;

Fig. 2 is another sectional view of the engine shown in Fig. 1 substantially at right angles 25 thereto;

Figs. 3 and 4 are detail sectional views showing the position of the valve for slow and high speed operation respectively;

Fig. 5 is a view, partly in section, showing an 30 oil control valve connected for operation with a carburetor;

Fig. 6 is a plan view of an oil control valve connected for operation with the spark adjusting plate of a magneto; and

Fig. 7 is a sectional view of an oil control valve, 35 a carburetor control, and magneto controlling means all operated in conjunction.

When an engine of this type runs at high speed a comparatively high ratio of oil to gasoline is 40 necessary for proper lubrication. The oil is carried along in the mixture of gasoline, vapor, oil globules and air, into the cylinder where the mixture is burned or carried out through the exhaust port. Under the high temperatures developed by such operation the excess oil does not 45 foul and short-circuit the spark plugs.

When the ordinary engine is then throttled and slowed down, less lubrication is necessary; the 50 excess oil carried into the combustion chamber is neither thoroughly burned nor scavenged through the exhaust port and it tends to collect or deposit on the insulator of the spark plug, causing short-circuiting of the plug, misfiring and stopping of the engine.

If a spark plug is used that will withstand the

temperature conditions of high speed in full throttle without getting sufficiently hot as to cause pre-ignition, then at slow speed and closed throttle it will foul and short-circuit. If a spark plug is used that will not foul at slow speed and closed 5 throttle, then under the temperatures of high speed and open throttle it will get too hot and cause pre-ignition. In the construction herein shown and described this difficulty is overcome by controlling the excess oil present at slow speed 10 and closed throttle.

Referring now more particularly to the drawings, a two-cycle type of engine is illustrated having a cylinder 6 with an attached closed crank case 7 in which a crank shaft 8 is rotatable carrying crank discs or arms 9 connected by a crank pin 10 to which one end of a piston rod 11 is journaled, the other end of the rod being connected to a piston 12 reciprocating in the cylinder.

At one side of the cylinder casing is a fuel inlet 13 leading from the crank case and terminating in a port or ports 14 within the cylinder and at the other side of the cylinder is an exhaust port 15 for the exhaust gases. In the outer end 25 of the cylinder is a spark plug 16 for igniting the charge which is admitted to the combustion chamber through the fuel passage 13 by a movement of the piston therein in a well-known conventional manner.

The present invention comprises a passage 20 formed in the wall of the casing 7 and communicating with the end of the fuel passage 13 in the cylinder wall. This passage 20 communicates with a passage 21 formed in the crank shaft 8 and extending through one of the arms 9 and terminating in an open port 22 located centrally thereof in the crank case chamber.

Extending laterally from the passage 20 and opening at the periphery of the crank case chamber is a port 23 and located in the chamber at this position is a rotatable valve 25 having a stem 26 extending externally of the casing for rotational movement by means of an arm 27 attached to the stem, or any other suitable operating 45 means, and the valve being movable by means of the arm either to close the port 23 and to open the passage 20 to form communication with the fuel passages 13 and 21 to the central portion of the crank case, for slow speed operation as shown 50 in Fig. 3, or to close the passage 20, opening the port 23 for direct communication with the fuel passage 13 from the periphery of the crank case as shown in Fig. 4. With this construction the valve 25 opens a direct passage from the periph- 55

ery of the crank casing at high speed and with the throttle open, there is no excess oil under this condition as it is carried out through the passage 13 to the cylinder. At slow speed with the 5 throttle closed the fuel mixture is taken from the center of the crank case through the passage 21.

The opening 22 of the slow speed passage 21 is located centrally of the crank case so that little oil will enter it as the oil in the mixture is 10 in relatively heavy globules which are thrown by centrifugal force of the whirling mixture in the crank case to the outside thereof. At slow speed a large portion of the excess oil in the mixture is therefore trapped in the crank case and does not 15 enter the fuel passage 13 or the cylinder and does not reach the spark plug to foul it. If this excess oil were not disposed of, then upon opening the valve 25 for high speed operation, the oil will be carried into the cylinder which would provide 20 excess oil to foul and short-circuit the spark plug.

A check valve is therefore located at the lower part of the crank case comprising a tubular member 30 connected by a passage 31 with the interior of the crank case having a ball valve 32 enclosed by a casing 33 and pressed to closing position by a spring 34. In the casing are outlets 35 through which oil from the interior of the crank case may escape through the check valve. 30 Whenever compression takes place in the crank case and sufficient oil has collected therein to flow into the passage 31 of the relief valve, a small portion of the oil, or other liquid, is forced through the check valve and so out of the crank 35 case. This oil is disposed of by pipes leading from the casing 33 or the openings 35 thereof in any suitable manner.

In order to make the excess oil control entirely automatic and dependent upon either throttle or 40 spark variation, or controlling all three together, the stem 26 of the control valve 25 is provided with an arm 40 (Figs. 5 and 6) attached by a set screw 41, pivoted to one end of a link 42, and the other end of the link is pivoted to an arm 43 attached to the throttle valve of a carburetor 44.

Or the engine may have a magneto with a rotating part 50 affixed to the shaft 8, and an adjustable armature plate 51 movable about the shaft by a projecting arm 52 to advance or retard 50 the engine spark in controlling the speed. To this plate is pivotally connected one end of a link 53, the other end being pivoted to an arm 54 connected to the control valve 25, so that the valve is opened and closed in accordance with the 55 manual control of the engine speed by the operation of the arm 52.

Both the carburetor control arm 43 and the magneto speed control plate 51 may be connected by their links 42 and 53 respectively to an 60 operating arm 56 of the valve 25, as shown in Fig. 7, for interconnecting these parts for joint and synchronous operation. The movement of one part correspondingly actuates all the others, but the normal manual operation is by the magneto 65 plate arm 52.

This construction therefore provides a simple and effective means for operation at both high and low speed; sufficient lubrication is provided for high speed operation; excess lubrication is 70 prevented at low speed operation; fouling of the spark plugs and the attendant difficulties are overcome; the collection of superfluous lubrication or liquid in the crank case is avoided; and operation of the lubricant controlling means may 75 be entirely automatic and dependent upon other

speed controlling means. Although the valve 25 is described as entirely open or entirely closed with respect to the port 23 and the passage 20, it is obvious that it may be partially open to both of them by placing it in an intermediate position. 5 The operation of this valve however will cause more efficient lubrication of the engine and therefore greater operating efficiency at the highest, lowest and intermediate speeds.

I claim:

1. A combustion engine having a compression chamber and an explosion chamber, means forming a passage between the chambers with an entry at the periphery and another adjacent the center of the compression chamber, and one or 15 more valves in the passages to control both entries to the passage.

2. A two-cycle, internal combustion engine comprising a pre-compression chamber, a crank rotatable therein, an explosion cylinder, means forming a passage between the chamber and the cylinder having an entry substantially at or in line with the center of the crank and another entry at the outer periphery of the compression chamber and a valve in the passage for controlling the flow of a combustible mixture either from 20 the center or the periphery of the chamber through the passage to the explosion cylinder.

3. A two-cycle, internal combustion engine having a compression chamber and an explosion 30 chamber, means forming a transfer passage between the chambers with an oil carrying entry and an oil free entry thereto from the compression chamber, valve means to control the entries, an automatic drainage valve in the compression chamber, the valve permitting excess oil 35 and other liquid to be ejected from said chamber due to pressure therein.

4. A two-cycle internal combustion engine having a compression chamber and an explosion cylinder, means forming a transfer passage between the chamber and the cylinder with outlets substantially at the center and periphery of the chamber, a valve for controlling both entries to the passage and a relief valve in the crank case 45 for automatically discharging excess liquid therefrom due to pressure therein.

5. A two-cycle internal combustion engine having a crank case compression chamber and an explosion cylinder, a piston movable in the cylinder and a crank for the piston rotatable in the crank case, a transfer passage between the chamber and the cylinder having means forming an entry substantially at the center of the crank case and another at the periphery thereof and valve 55 means to control both entries to the passage for varying the amount of compressed charge which is taken from the center or from the periphery of the crank case and thereby varying the lubrication carried with the fuel charge into the combustion cylinder.

6. In an internal combustion engine having a compression chamber, an explosion chamber, means forming a transfer passage between the chambers, a control valve in the passage, a magneto having a movable spark control plate, a carburetor having a movable throttle control arm, and means interconnecting the plate, the arm and the valve for joint operation.

7. In an internal combustion engine the combination with a combustion chamber, a crank case and a crank shaft mounted to rotate in the crank case and to tend to effect centrifugal separation of oil from gases therein, of a piston reciprocable in the combustion chamber and adapted to com- 70

press alternately the gases in said crank case and said chamber, said piston being operatively connected with the crank shaft, means providing a transfer passage leading to the combustion chamber and communicating at a plurality of points with the crank case, one of said points being nearer than the other to the axis of the crank shaft, and valve means controlling communication of said passage with said crank case at at least one of said points.

8. An internal combustion engine comprising in combination a cylinder providing a combustion chamber, a crank case communicating therewith, a piston reciprocable in the cylinder to compress gases alternately in the combustion chamber and in the crank case, a crank shaft with which said piston is operatively connected, said crank shaft being rotatable in the crank case and tending to effect centrifugal separation of oil from gases contained in the crank case, means providing a transfer passage leading to said combustion chamber and provided with branches separately communicating with the crank case, one of said branches opening at a point adjacent the axis of said crank shaft and another of said branches opening from the crank case at a point remote from the axis of said crank shaft, and valve means for selectively controlling the communication of said passage with said crank case through one of said branches or the other.

9. An internal combustion engine comprising in combination a cylinder providing a combustion chamber, a crank case communicating therewith, a piston reciprocable in the cylinder to compress gases alternately in the combustion chamber and in the crank case, a crank shaft with which said piston is operatively connected, said crank shaft being rotatable in the crank case and tending to effect centrifugal separation of oil from gases contained in the crank case, means providing a transfer passage leading to said combustion chamber and provided with branches separately communicating with the crank case, one of said branches opening at a point adjacent the axis of said crank shaft and another of said branches

opening from the crank case at a point remote from the axis of said crank shaft, and valve means for selectively controlling the communication of said passage with said crank case through one of said branches or the other, together with engine speed control means having advanced and retracted positions and a connection from said engine speed control means to said valve means for actuating said valve means to a position such that in the advanced position of the speed control means said valve means will place said passage in communication with the crank case through the branch opening remote from said crank shaft axis.

10. An internal combustion engine comprising in combination a cylinder providing a combustion chamber, a crank case communicating therewith, a piston reciprocable in the cylinder to compress gases alternately in the combustion chamber and in the crank case, a crank shaft with which said piston is operatively connected, said crank shaft being rotatable in the crank case and tending to effect centrifugal separation of oil from gases contained in the crank case, means providing a transfer passage leading to said combustion chamber and provided with branches separately communicating with the crank case, one of said branches opening at a point adjacent the axis of said crank shaft and another of said branches opening from the crank case at a point remote from the axis of said crank shaft, and valve means for selectively controlling the communication of said passage with said crank case through one of said branches or the other, together with engine speed control means having advanced and retracted positions and a connection from said engine speed control means to said valve means for actuating said valve means to a position such that in the retarded position of said engine speed control said valve means will be adjusted to place said passage in communication with the crank case through the branch which opens to the crank case adjacent the axis of said crank shaft.

PHILIP A. TANNER.
